CLAIM

The ornamental design for a multi-capacitor assembly, as shown and described.

DESCRIPTION

FIG. 1 is a top, side and end perspective view of a multi-capacitor assembly showing our new design.

FIG. 2 is a bottom, side and opposite-end perspective view of a multi-capacitor assembly showing our new design.

FIG. 3 is a top plan view thereof.

FIG. 4 is a bottom plan view thereof.

FIG. 5 is a first side view thereof.

FIG. 6 is an opposite side view thereof.

FIG. 7 is a first end view thereof; and,

FIG. 8 is an opposite end view thereof.

Broken lines and alphanumeric characters in the figures are for illustrative purposes only and form no part of the claimed design.
